UNITED STATES PATENT OFFICE

154,622

DESIGN FOR A FLY SWATTER

Ernest P. Moslo, Cleveland, Ohio

Application August 21, 1947, Serial No. 140,972

Term of patent 14 years

(Cl. D31—3)

To all whom it may concern:

Be it known that I, Ernest P. Moslo, a citizen of the United States, residing in Cleveland, in the county of Cuyahoga, State of Ohio, have invented a new, original, and ornamental Design for Fly Swatters of which the following is a specification, reference being had to the accompanying drawing, forming a part thereof.

Fig. 1 is a front elevational view of a fly swatter showing my new design;

Fig. 2 is a side elevational view thereof; and

Fig. 3 is a transverse sectional view taken through the body of the fly swatter along the line 3—3 of Fig. 1.

The characteristic features of my design reside in the portion shown in full lines.

I claim:

The ornamental design for a fly swatter, substantially as shown and described.

ERNEST P. MOSLO.
